CLAIM

We claim the ornamental design for a horizontal bat rack, as shown and described.

DESCRIPTION

FIG. 1 is a top, front, and left side perspective view of a horizontal bat rack showing our new design;

FIG. 2 is an enlarged front elevation view thereof;

FIG. 3 is an enlarged rear elevation view thereof;

FIG. 4 is an enlarged top plan view thereof; and,

FIG. 5 is an enlarged bottom plan view thereof.

FIGS. 2-5 are shown broken-away for convenience of illustration.
